UNITED STATES PATENT OFFICE.

WALTER F. ROGERS, OF CHICAGO, ILLINOIS.

RACK.

Application filed June 24, 1925. Serial No. 39,239.

The main objects of this invention are to provide an improved form and arrangement of rack for removably supporting the burners and drip pan of a gas range; and to provide a one-piece sheet metal rack of the above kind which is inexpensive and durable, and which may be readily attached to the range.

An illustrative embodiment of this invention is shown in the accompanying drawings, wherein:

Fig. 1 is a perspective view of a gas range to which an improved rack is applied, parts of the stove being broken away or omitted for the sake of clearness.

Fig. 2 is an enlarged perspective view of a rack.

Fig. 3 is an enlarged detail in perspective of one of the burners.

In the embodiment herein shown the improved rack is applied to a common type of gas range comprising side walls 1, and a back wall 2, reinforced by corner angle bars 3 and mounted on a base plate 4, which is supported on legs 5. A drip pan 6 and a plurality of burners 7 are supported in the upper part of the stove by the improved rack which embodies this invention.

In the specific construction herein shown, the improved rack comprises a pair of substantially channel-shaped members 8, mounted on the side walls 1 and disposed substantially horizontally for supporting the drip pan 6 and a pair of rods 9, on which the burners 7 are supported.

The members 8 are preferably made of sheet metal and are identical in construction. Each of the channel members 8 comprises a web 10 and legs or flanges 11 and 12 bent at substantially right angles thereto. Formed in the web 10, are apertures 13 to receive bolts 14 or other suitable fastening means for securing the rack to the side walls 1. The lower flanges 11 provide shelves for slidably supporting the drip pan 6, which is movable through the front end of the stove. A portion of the upper flange 12 is bent upwardly to provide an upstanding ledge 15, which is offset from the plane of the web

10 so as to be spaced inwardly from the side walls 1 of the stove. Formed in the upper edges of the ledges 15, are recesses or notches 16, which provide seats for loosely supporting the ends of the rods 9. Any number of rods 9 may be used, depending upon the number of burners which it is desired to support. In the form shown, two rods 9 are employed for supporting four burners.

The burners 7 may be of any desired shape, and are provided with mixing tubes 17 which communicate with the usual manifold (not shown) at the front of the stove. In the embodiment herein shown, the burners 7 are of star shape, and are cast integral with the mixing tubes 17. Projecting downwardly from two of the arms of each burner, is a pair of lugs or supporting legs 18, which are recessed at their lower ends, as shown at 19, for engaging the rods 9.

From the foregoing description it will be apparent that this improved rack provides a convenient means for supporting the burners and drip pan, and permits the parts to be readily assembled and dismantled.

Although but one specific embodiment of this invention has been herein shown and described it will be understood that numerous details of the construction shown may be altered or omitted without departing from the spirit of this invention as defined by the following claim.

I claim:

A rack of the class described comprising a web adapted to be secured in vertical position, a flange extending along the lower edge thereof for supporting a tray, another flange extending along the upper edge of said web and bent at substantially right angles thereto, and a ledge formed by bending the outer edge of said upper flange to a plane substantially parallel to said web and offset therefrom, said ledge having a recess therein providing a seat for a removable burner support.

Signed at Chicago this 22 day of June 1925.

WALTER F. ROGERS.
